ATTORNEY

UNITED STATES PATENT OFFICE

EDWIN S. MIX, OF ROCHESTER, NEW YORK, ASSIGNOR TO HICKOK MANUFACTURING COMPANY, INC., OF ROCHESTER, NEW YORK

BELT FOR PERSONAL WEAR

Application filed September 18, 1927. Serial No. 219,898.

The present invention relates to belts for personal wear, and an object thereof is to provide a construction which will make it possible to obtain an overlapping end portion which will be uniform in length notwithstanding the size of the waist of the wearer. Another object of the invention is to provide a belt having elastic means incorporated therein adjacent the overlapping end of the belt so that the belt will be inconspicuous in use. Still another object of the invention is to provide a means arranged on the rear face of a belt near the overlapping end for detachably engaging with a belt buckle so that the overlapping end may be passed through the buckle and cover both connections of the belt with the buckle.

To these and other ends, the invention consists of certain parts and combinations of parts all of which will be hereinafter described: the novel features being pointed out in the appended claim.

In the drawings:

Fig. 1 is a rear face view of the two ends of a belt secured to a buckle in accordance with this invention, parts of the belt being broken away;

Fig. 2 is a section on the line 2—2, Fig. 1;

Fig. 3 is a rear face view of a buckle employed in another embodiment of the invention;

Fig. 4 is an inside view of the overlapping belt end employed in connection with the buckle illustrated in Fig. 3;

Fig. 5 is a rear face view of two ends of a belt connected to the buckle illustrated in Fig. 3; and

Fig. 6 shows in side elevation one of the belt anchoring devices of the buckle shown in Fig. 3 arranged in proximity to the elastic connection.

In the embodiment of the invention illustrated in Figs. 1 and 2, 1 indicates a front plate of a buckle frame having side flanges 2 extending rearwardly and inwardly.

Two anchoring devices are mounted on the side flanges 2 in spaced relation to the rear face of the front plate 1. In this instance, one of these anchoring devices comprises a swinging loop 3 pivoted at 4 to the side

flanges and having the belt end 5 preferably detachably secured thereto. In order that the belt may be made to fit different waist measurements the belt is fitted about the wearer and its end 5 is cut to accommodate it to the 55 waist measurement. The cut end is then secured to a clamp comprising, in this instance, two plates 6 and 7 pivoted to each other at 8, one of said plates having an opening 9 into which the belt is forced by a lateral clamping 60 lip 10 on the other member. The members also have at their free ends lateral lips 11 and 12 one of which snaps over the other to engage with the loop 3 and detachably hold the belt end 5 to the buckle frame. The other belt 65 end anchoring means, in this instance, comprises a bar 13 connecting the side flanges of the buckle frame and serving to detachably secure the opposite end 14 of the belt. The latter for this purpose has an anchoring 70 means on its rear face in spaced relation to its extreme end and on the rear side thereof for engaging the bar so that that portion of the belt beyond the anchoring means thereon may be passed between the rear face of the 75 front plate and the two anchoring means on the buckle frame so that the other end 5 of the belt as well as all connections of the belt with the buckle frame are hidden from view by the overlapping end of the belt. At 80 the same time, the overlapping end at all times projects substantially an equal amount for any waist measurement.

It is also preferred to employ with the belt, an expansion device permitting the belt to 85 adjust itself to different positions of the user. To this end, the belt end 14 is provided with a pocket 15 lying between the two side edges of the belt and containing a guide member 16, in this instance in the form of a plate. 90 In this plate are guided two guide bars 17 which operate in the pocket 15 and through two openings 18 in the rear layer or face member of the belt. These guide bars, in this instance, are connected by a hook 19 95 which forms an anchoring device on the rear face of the belt in spaced relation to the overlapping belt end for detachably engaging about the anchoring bar 13.

Spring means of any suitable construction 100

may be employed for opposing the movement of the anchoring device 19 relatively to the guide 16. In this instance, two springs 20 surround the guide bars 17 within the pocket

15 and abut the guide 16 and also a cross piece 21 which connects the inner ends of the guide bars 17. Stitches 22 may be passed through the belt on opposite sides of the guide 16 to hold the latter against movement in the pocket 15.

10 In the embodiment shown in Figs. 3 to 6 inclusive, the belt end 5 is secured to a loop or anchoring member 3 like the embodiment illustrated in Figs. 1 and 2. The anchoring

15 means at the other end of the buckle frame is different and comprises a bar 13^a with a headed projection 13^b on the rear face thereof. This headed projection is adapted to pass into the narrow portion of a bayonet slot

20 19^a in a plate 19^b which is pivoted at 19^c to a cross piece 19^d connecting the two ends of two guide bars 17^a which operate through openings 18 in the rear layer of the belt end 14 to extend into a pocket 15 which encloses

25 a guide 16 and spring means opposing the movement of the two bars 17^a. In this instance, the two guide bars are formed in one piece with a cross bar 21^a, and a single spring surrounds both bars 17^a and the cross piece 30 and has its ends in abutment with the guide 16.

35 In both embodiments of the invention, the two anchoring means on the belt buckle are spaced from the rear face of the front plate

40 while an anchoring means is provided on the inner face of the belt in spaced relation to the overlapping end to engage one of the anchoring means so that the overlapping end of the belt may pass between the front plate of the

45 buckle frame and the two anchoring means on the buckle frame to cover both anchoring means. This arrangement makes it possible to obtain an overlapping end of substantially uniform length in belts, notwithstanding

50 variations in waist measurements. An elastic or expansion means is so arranged adjacent the overlapping belt end that it is inconspicuous and, at the same time, provides for an overlapping end of substantially uniform length in different waist measurements.

55 What I claim as my invention and desire to secure by Letters Patent is:

60 The combination with a belt, and belt buckle secured at one end to the belt, the belt having adjacent its opposite end a pocket between its side edges opening on the rear face of the belt end in which the pocket is formed and in spaced relation to the last mentioned end, of a guide in the pocket, two guide bars movable on the guide, spring means in the pocket opposing the movement of the guide bars, an anchoring device connected to the guide bars and lying behind that belt end in which the pocket is formed,

and an anchoring device on the buckle with which the anchoring device carried by the guide bars cooperates to hold the belt end to the buckle.
